UNITED STATES PATENT OFFICE.

PATRICK CONNOLLY, OF NEW YORK, N. Y.

SNOW-MELTING APPARATUS.

1,388,027.

Specification of Letters Patent. Patented Aug. 16, 1921.

Application filed August 19, 1918. Serial No. 250,432.

To all whom it may concern:

Be it known that I, PATRICK CONNOLLY, a citizen of the United States, residing at New York city, in the county of Kings and State of New York, have invented certain new and useful Improvements in Snow-Melting Apparatus, fully described and represented in the following specification and the accompanying drawings, forming

10 a part of the same.

This invention relates to snow melting apparatus. The removal of snow from city streets, and especially from the streets of large cities, presents a serious problem. 15 The snow cannot be dumped into the sewers in any considerable quantity because of the danger of blocking the sewers, and it is necessary, therefore, quite generally to haul the snow for comparatively long distances to places suitable for disposal thereof.

20 The present invention has been made especially with the idea of providing apparatus suitable for installation at various points throughout a city so that snow from a district to be served by any particular apparatus need be hauled only a comparatively short distance to the apparatus and dumped into the apparatus to be quickly melted, the resulting water being discharged into the 25 sewer without harm.

30 The invention aims to provide a snow melting apparatus which may be permanently located beneath the surface of a city street or at any other suitable and convenient location beneath the surface of the ground, so as to be available for use when desired and so that the snow from the collection carts may be dumped directly into the receiving opening of the apparatus.

35 The invention aims further to provide an apparatus which shall be of comparatively simple and durable construction and of high melting efficiency and adapted for adjustment as to the degree of heat developed and manner of use according to the amount and character of the snow to be melted, and which, if located beneath the surface of the ground, shall not when not in use interfere with the use of the street or other place 45 where the apparatus is located.

40 A full understanding of the invention can best be given by a detail description of a preferred form of apparatus embodying the various features of the invention, 45 and such a description will now be given in connection with the accompanying draw-

ings illustrating such an apparatus, and in which:

Figure 1 is a sectional view of such an apparatus; and

Fig. 2 is a top plan view of the apparatus with interior parts and fitting thereof indicated by dotted lines, the cover of the oil tank chamber, which is shown in place in Fig. 1, being removed.

50 Referring to the drawings, the apparatus comprises means providing a melting chamber 10, which in an apparatus comprising all the features of the invention and as illustrated is formed by a pit sunk below the level of the ground and having side retaining walls 11, a water retaining bottom wall 12, and a top or cover wall 13. When the pit is located beneath the pavement of a street, the top wall 13 may be made to serve 55 as a part of the street pavement above the pit, or may be at such a level that the regular street pavement will be extended over and supported by the top wall. Extending downward into the chamber from the top 60 wall 13 is a metal chute 14 for receiving the snow to be melted, which at its upper end is of suitable size and shape in cross-section so that a load of snow from a collecting cart may be dumped directly therein. 65 The chute most desirably extends vertically downward, and terminates a short distance from the bottom of the pit, ordinarily about three feet from the bottom, and is open at its lower or discharge end. It is most desirably comparatively long in one direction 70 and narrow in the other in cross-section, with its opposite side walls inclined slightly inward toward each other in the downward direction so that the smaller cross-dimension of the chute gradually decreases from 75 its upper to its lower end.

80 Extending about the chute is a casing 15 which is spaced away from the walls of the chute and is best made to flare outward 100 somewhat in the direction from its upper to its lower end so that the space between the casing and the chute shall be of decreasing cross-area in the direction from the lower to the upper portion thereof. 105 From the upper end of the casing 15, a connecting casing 16 leads off to an outlet opening 17 through the top wall 13, providing an outlet passage from the upper end of the space between the casing 15 and the 110 chute for the discharge of the products of combustion as hereinafter explained. A

- discharge pipe or drain outlet 20 leads from the lower part of the chamber or pit to connect with the sewer for carrying away the water resulting from the melting of the snow, the intake end of this pipe opening to the chamber at a point above the bottom of the chamber and most desirably slightly below the lower or discharge end of the chute. The purpose of having the intake opening of this pipe located above the bottom of the chamber is to maintain in the operation of the apparatus a body of water in the bottom of the chamber and to conduct away water which collects therein above the level of the pipe opening, the bottom of the chamber thus serving as a mud pit or sump for the collection of mud and substances of various sorts which it is undesirable to have discharged into the sewer. The intake opening of the discharge pipe 20 will be protected by a suitable guard netting 21.
- Arranged about the chute 14 are a plurality of burner nozzles 25 arranged to direct heating flames against the sides of the chute. The apparatus will usually be arranged for the use of oil as fuel, and it will usually be desirable to construct the apparatus so that the oil on its way to the burners will be vaporized and discharged from the burners in the form of oil vapor. In the apparatus shown the oil is supplied from a tank 30 located in a tank chamber provided adjacent the melting chamber, the oil being forced from the tank in the ordinary manner by means of air pressure supplied to the interior of the tank from an air pump 31 discharging into the tank past a check valve 32. The oil is forced from the tank through a supply pipe 33 which extends into the melting chamber or pit, and branches, one branch leading downward to a heating coil 34 on one side of the tank, and the other branch to a heating coil 34^a on the other side of the tank. From the two coils, connection is made by pipe 35 to headers 36, one on each side of the chamber, from which connection is made to the nozzles 25, which are arranged in two series, one on each side of the chute. The supply pipe 33 is provided with a valve 33^a which serves as a shut off valve and also as an adjusting valve by which the amount of oil burned and the amount of heat supplied for melting the snow may be varied and regulated as desired. The nozzles 25 are most desirably located to discharge through openings 37 formed in the casing 15 as shown. The burner nozzles are or may be of any suitable Bunsen burner construction for discharging the oil vapor with some air drawn from the space outside the casing mixed therewith, and additional air for supporting combustion will enter 65 through the burner openings 37 in the cas-

ing. For supplying the air for supporting combustion, an opening 38 is provided in the top chamber wall 13, which opening also serves as a manhole for entrance to the chamber.

In addition to the burner nozzles 25, additional burner nozzles 40 similar to the nozzles 25 are provided arranged in two series, one on each side of the chute, and set to discharge in the direction of the space 75 below and on each side of the lower or discharge end of the chute. The flames from these nozzles 40 will thus be directed against the surface of the body of water in the bottom of the pit or chamber and against any 80 snow which, falling unmelted through the chute, may collect in or float on the surface of such water. These nozzles 40 are connected with and supplied with oil vapor from headers 41 connected with the pipes 85, 35 leading from the vaporizing coils 34 and 34^a.

Extending about the sides of the pit or chamber slightly above the level of the intake opening of the discharge pipe 20, is a 90 shelf 43 on which a man may stand in cleaning the bottom of the pit or in making repairs or adjustments of the apparatus. This shelf also serves as a convenient support for the heating coils 34 and 34^a for 95 supporting the coils in position to be heated by the flames from the lower nozzles 40.

Suitable covers are provided for the openings 17 and 38 and for the snow receiving opening at the upper end of the chute. The 100 covers for the openings 17 and 38 are removed when the apparatus is in use, and these covers, 46 and 47, are indicated merely by dotted lines in Fig. 1. The cover 48 for the chute opening, which is shown closed 105 in Fig. 1, will usually be left closed during the use of the apparatus except when snow is to be dumped into the chute. The chute cover 48 is most desirably made, as shown, in two parts hinged at the sides of the opening and connected by gear segments 49 so as to be opened and closed together by a single operating hand rod or lever 50 which is made detachable. The cover may thus be opened, as shown in Fig. 1 by dotted 110 lines, after a bottom-dump wagon or cart has been driven over the chute opening. It will usually be desirable to provide means for increasing the flow of air into the melting chamber and of the products of combustion from the space between the chute and the casing 15. For this purpose it will usually be sufficient to provide a short chimney or draft pipe 55 to be connected at the outlet opening 17 and to be removed when 125 the apparatus is not in use.

In using the apparatus as so far described, the covers 46 and 47 being removed from the openings 17 and 38 and the draft pipe being provided at the opening 17, and 130

there being suitable air pressure in the oil tank to force the oil through the supply pipe leading to the burners, the valve 33^a will be opened and the jets from the burners will be lighted to heat up the apparatus, usually before dumping snow into the chute. The heating coils 34 and 34^a may be heated for vaporizing the oil at the start in any suitable manner, as by lighting some oil-soaked waste placed on the coils. When the coils are heated, the oil passing through them under pressure from the tank is vaporized and jets of oil vapor and air are discharged from the burner nozzle, additional air for the jets from the nozzles 25 flowing through the openings 37 and beneath the bottom of the casing 15. The products of combustion rising in the space between the chute and the casing 15, give up heat to the walls of the chute and escape through the outlet opening 17 and draft pipe 55. Fresh air will thus be constantly drawn into the chamber through the opening 38, and free and intense combustion will be maintained with the development of the required heat. When snow is dumped into the chute 14, the chute cover being opened, and being most desirably closed between dumpings in order to prevent loss of heat, the snow will be more or less melted within the chute. Because of the downwardly tapering form of the chute, the snow is prevented from falling in large quantities directly through the chute and tends to collect therein, wedging against the side walls of the chute. These side walls being intensely heated by the flames from the nozzles 25, the snow which is against the walls is rapidly melted, so that the mass of snow which has become wedged in the chute will move gradually downward therethrough, the water and unmelted snow finally being discharged into the bottom of the pit below the discharge end of the chute, such unmelted snow thus coming within range of the flames from the lower nozzles 40. The bottom of the chamber may contain a body of water up to a level not higher than the intake opening of the outlet pipe 20 at the beginning of the operation. If not, water resulting from melting the snow will collect in the bottom of the pit until it reaches the discharge level. Additional water collecting in the pit will be drained off through the pipe 20. Unmelted snow and ice will be prevented from entering the discharge pipe by the guard netting 21, and pieces of wood, stone, etc., which might clog the discharge pipe or which it is undesirable to have enter the sewer will also be held back by the guard netting. Such articles and dirt or mud which may be dumped into the chute with the snow will thus collect in the bottom of the pit to be removed from time to time through the opening 38 as may be necessary.

By adjusting the valve 33^a, the burner flames may be regulated according to the amount of snow to be melted and the degree of heat required.

The apparatus is most desirably provided with means for discharging a plurality of jets of water directed toward the space below and adjacent to the lower or discharge end of the chute 14. For this purpose, in the apparatus shown, a water supply pipe 60 controlled by a valve 61 is led into the melting chamber and connected by branch pipes 62 to headers 63 located one on each side of the chute and casing 15 and provided each with a plurality of discharge nozzles 64 positioned to direct jets of water downwardly and inwardly toward the space below and adjacent to the lower end of the chute. The supply pipe 60 and valve 61 should be located deep enough in the ground to avoid freezing, and the valve may be operated by a key-rod 65 extending upward, or by other suitable means. The use of water jets will not always be necessary in the operation of the apparatus, but such jets, even when the water is at the usual supply temperature, will aid substantially in the melting of snow which passes through the chute into the bottom of the chamber and will thus reduce the amount of fuel necessary to be used. The effect of the water jets discharged from the nozzles 64 is greater if the water is heated, and where a supply of heated water is not available, this being usually the case, the apparatus may be provided with means for heating the water supplied to the nozzles 64. Any suitable heating means may be provided for this purpose, and in Fig. 1 of the drawings a coil heater 66 is shown connected between the supply pipe 60 and the branch pipes 62. The burner of this heater may be supplied with oil from the tank 30, a separate supply pipe 67 having a control valve 68 being shown for this purpose.

The apparatus illustrated is also provided with a steam heating coil 70 extending about the sides of the bottom portion of the melting chamber so as to heat the body of water standing therein, such coil as shown being supplied with steam through a pipe 71 leading upward and into the oil tank chamber for connection to a pipe from a source of steam supply. From the other end of the coil a vent pipe 72 extends upward into the chamber. This additional heating means may be used in conjunction with the main heating means when an unusually large amount of snow is to be melted, or in unusually severe weather, or the heating coil alone, or the water jets alone, or the two together without the main heating means, may

be used to heat the body of water standing in the lower part of the chamber when only a comparatively small amount of snow is to be melted, the snow in such case all passing

5 downward through the chute to be melted after being discharged from the chute into the body of water in the bottom of the pit.

It is to be understood that the invention is not to be limited to the exact construction, 10 arrangement and combinations of parts shown and to which the foregoing description has been largely confined, but that it includes changes and modifications thereof within the claims. For example, while the 15 invention has been made especially with the idea of providing an apparatus to be located entirely below the surface level of the ground, features of the invention may obviously be embodied in apparatus not so 20 located.

What is claimed is:

1. Snow melting apparatus, comprising in combination a melting chamber, a chute extending downward into the chamber for receiving snow to be melted, a heat confining casing located within the melting chamber and extending about the chute and spaced therefrom, a burner nozzle for directing a heating flame against the outside of said 25 chute within the casing, means for supplying air to said chamber, means providing an outlet passage for the products of combustion leading from the upper part of said casing, and a drain outlet leading from the 30 lower part of said chamber.

2. Snow melting apparatus, comprising in combination a melting chamber, a chute of downwardly tapering form extending vertically downward into the chamber for receiving 40 the snow to be melted and having its discharge opening located near the bottom of the chamber, a plurality of burner nozzles arranged about the chute, some of said nozzles being positioned to direct heating flames 45 against the outside of the chute and some being arranged to direct heating flames downwardly toward the space adjacent and below the lower end of the chute, and a drain outlet leading from the lower part of the 50 chamber.

3. Snow melting apparatus, comprising a heating chamber, a chute extending downward into the chamber, a heat confining casing arranged about said chute and spaced 55 therefrom and having burner openings therein, burner nozzles set to discharge through the burner openings in the casing and against the chute, other burner nozzles set to discharge downwardly toward the space adjacent and below the lower end of the chute, means for supplying fuel to said burner nozzles, means for supplying air to said chamber, means providing an outlet passage for the products of combustion leading from the 60 upper end of said casing, and a drain outlet

leading from said chamber below the level of the lower end of the chute and above the bottom of the chamber.

4. Snow melting apparatus, comprising a downwardly extending chute for receiving the snow to be melted, a casing arranged about said chute and spaced therefrom, means for causing the combustion of fuel between said chute and said casing for heating the walls of the chute, means for withdrawing the products of combustion from the upper end of the space between the chute and said casing, means for supplying heat directly to unmelted snow passing out from the lower end of the chute, and means for discharging water produced by the melting of the snow.

5. Snow melting apparatus, comprising a downwardly extending and downwardly tapering chute for receiving the snow to be melted, a casing arranged about said chute and spaced therefrom, means beneath the discharge end of the chute for retaining unmelted snow discharged from the chute, means for directing heating flames against the outside of the walls of the chute, and means for directing heating flames downward toward the space adjacent and below the lower end of the chute.

6. Snow melting apparatus, comprising a melting chamber formed by a pit sunk beneath the surface of the ground and having side walls and a top wall, a chute extending downward from the top wall into the pit for receiving the snow to be melted, a plurality of burner nozzles arranged some to direct heating flames against the sides of the chute and some to direct heating flames downwardly toward the space below the discharge end of the chute, means for supplying fuel to said burner nozzles, means for supplying air for supporting combustion, means for conducting the products of combustion from the pit, and a water discharge pipe leading from the lower part of the pit at a point some distance above the bottom thereof.

7. Snow melting apparatus, comprising a melting chamber formed by a pit sunk beneath the surface of the ground and having side walls and a top wall, a chute extending downward from the top wall into the pit for receiving the snow to be melted, a plurality of burner nozzles arranged some to direct heating flames against the sides of the chute and some to direct heating flames downwardly toward the space below the discharge end of the chute, means for supplying fuel to said burner nozzles, means for supplying air for supporting combustion, means for conducting the products of combustion from the pit, a water discharge pipe leading from the lower part of the pit at a point below the level of the lower end of the chute and above the bottom of the pit,

- and means for directing jets of water toward the space below the lower end of the chute.
8. Snow melting apparatus, comprising a melting chamber formed by a pit sunk beneath the surface of the ground and having side walls and a top wall, a chute extending downward from the top wall into the pit for receiving the snow to be melted, a heat confining casing arranged about the chute and spaced therefrom, burner nozzles set to discharge against the sides of the chute within the casing, other burner nozzles set to discharge downwardly toward the space adjacent and below the lower end of the chute, means for supplying fuel to said burner nozzles, an air inlet opening in the top wall, an outlet opening in the top wall, a passage leading to said outlet opening from the upper end of the space between the chute and said casing, and draft inducing means for enhancing the flow of air into the chamber and the products of combustion from the space within the casing.
9. Snow melting apparatus, comprising a melting chamber formed by a pit sunk beneath the surface of the ground and having side walls and a top wall, a chute extending downward from the top wall into the pit for receiving the snow to be melted, heating means associated with the chute for melting snow in its passage through the chute, a water discharge pipe leading from the lower part of the pit at a point above the bottom thereof, water discharge nozzles for directing jets of water toward the space below the lower end of the chute, and means for heating water supplied to said nozzles.
10. Snow melting apparatus, comprising a melting chamber formed by a pit sunk beneath the surface of the ground and having side walls and a top wall, a chute extending downward from the top wall into the pit for receiving the snow to be melted, external heating means associated with the chute for heating snow in its passage through the chute, a water discharge pipe leading from the lower part of the pit at a point above the bottom thereof, and a heating coil arranged in the bottom of the pit below the intake opening of the water discharge pipe for heating water standing in the bottom of the pit.
11. Snow melting apparatus, comprising a melting chamber formed by a pit sunk beneath the surface of the ground and having side walls and a top wall, a chute extending downward from the top wall into the pit for receiving the snow to be melted, external heating means associated with said chute, a cover for the mouth of said chute formed of two parts hinged at the sides of the chute mouth to turn upward to open position, and a water discharge pipe leading from the lower part of the pit at a point above the bottom thereof.
12. Snow melting apparatus, comprising a melting chamber, the bottom of which forms a receptacle for water, a discharge pipe leading from said receptacle at a point above its bottom, a chute for receiving snow to be melted extending into said chamber from the top thereof to a point above the level of said discharge pipe, and means for directing a plurality of jets of hot water against the snow discharged from said chute and floating upon the water in said receptacle.
13. Snow melting apparatus, comprising a receptacle for holding water, a discharge pipe leading from said receptacle at a point above its bottom, a snow receiving chute above said receptacle and adapted to discharge snow upon the water in said receptacle, and fuel jets directed against the snow discharged from said chute and floating upon the water in said receptacle.
14. Snow melting apparatus, comprising a snow receiving chute greater in length than in cross-section and gradually tapering from its top to its bottom, external heating means surrounding said chute, a receptacle for water below the lower end of said chute, a discharge pipe leading from said receptacle at a point above its bottom, and means for heating the snow discharged from said chute and floating upon the water in said receptacle.

In testimony whereof I have hereunto set my hand in the presence of two subscribing witnesses.

PATRICK CONNOLLY.
